UNITED STATES PATENT OFFICE.

LEO HOLTSCHNEIDER, OF JEFFERSON CITY, MISSOURI.

GAS-BURNER AND AUTOMATIC CUT-OFF THEREFOR.

No. 841,400.

Specification of Letters Patent.

Patented Jan. 15, 1907.

Application filed April 27, 1906. Serial No. 313,935.

To all whom it may concern:

Be it known that I, LEO HOLTSCHNEIDER, a citizen of the United States, residing at Jefferson City, county of Cole, and State of Missouri, have invented a certain new and useful Improvement in Gas-Burners and Automatic Cut-Offs Therefor, of which the following is a specification.

My invention relates to a new and useful improvement in gas-burners and automatic cut-offs therefor, and has for its object to provide an exceedingly simple and effective device of this description which absolutely prevents the escape of gas in quantities sufficient to do damage should the light become extinguished.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a section of my improved burner; Fig. 2, a vertical section thereof, taken at the line *x x* of Fig. 1; Fig. 3, a section at the line *y y* of Fig. 1; Fig. 4, a detail view of the base, a portion of which is sectioned away; Fig. 5, a plan view of said base; Fig. 6, a detail view of the thermostat.

In carrying out my invention as here embodied, A represents the base, provided with the screw-threads B for attachment to the gas-fixture in the usual manner, and C is the pillar, which is adapted to fit over the base and secured thereto by means of the set-screw D. The base has formed in its upper end a concave recess E, and an opening F passes through this concave section slightly to one side of the center of the base for the purpose hereinafter set forth.

The groove G is formed around the base, and a hole H leads from said groove to the interior thereof in order that a small amount of gas may flow from the interior of the base to this groove and from thence through the passage I to reach the interior of the pillar C, and I provide a regulating-screw J, the inner end of which approximately fills the cross-

section of this passage I, so that by adjusting 55 said screw more or less gas will be permitted to flow through said passage.

K is a ball, made of any suitable material, placed upon the concave surface of the base. This ball normally rests over the opening F, 60 thus closing the principal flow of the gas from the base to the pillar.

L is a thermostat, which is made of two metals of different expansive properties, such as silver-solder (indicated at *a*) and steel, (indicated at *b*.) the steel being comparatively thin and offering but little bending resistance, the silver-solder being thicker. The silver-solder strip *a* extends upon one side of the steel strip *b* for about one-third of the 70 length of the thermostat, and then these two strips cross each other, each being on the opposite side for the remaining length of the thermostat.

The thermostat is attached to or terminates in the plate M, which is of some material that readily absorbs heat, and this plate is secured in the tip N, the latter being of a material of low heat-conducting power, having a slot O for the issuance of the gas for 80 forming the blaze.

When the gas is shut off at the stop-valve, the ball will rest upon the opening F; but when the gas is turned on the first action will be for a small portion to flow through the 85 hole H and passage I to the interior of the pillar and from thence escape through the slot O, from which point it may be lighted, and the burning of this small flame will transmit sufficient heat to the plate M to so affect 90 the thermostat as to cause it to force the ball from off the opening F, thus allowing the full flow of gas to reach the slot O and produce the full-size flame. Should the light become extinguished accidentally, the immediate cooling of the thermostat will permit the ball to again close the passage F thereof, shutting off the main flow of gas, the only escape being through the hole H and passage I, which is not sufficient to do any 100 damage.

The construction of the thermostat is such that it is self-compensating, so that the lower end is the same distance from the ball in either warm or cold surroundings.

The action of the thermostat upon the ball may be varied by adjusting the pillar around the base, which may be accomplished

by backing off the set-screw D and resetting it when the proper adjustment is had, it being understood that the turning of the pillar relative to the base will vary the position of the opening F relative to the lower end of the thermostat, and as the ball normally rests over this opening it follows that its normal position will also be varied relative to the lower end of the thermostat and this adjustment will cause the thermostat to act more quickly upon the ball.

P represents the sponge or other suitable material located within the base for filtering the gas in its passage to the pillar.

Having thus fully described my invention, what I claim as new and useful is—

1. The herein-described combination of a base threaded for application to a gas-fixture, said base having an upper concave surface and an opening through said surface off the axial line, said base also having a groove around its circumference and a hole leading from the interior thereof to said groove, a pillar adjustably fitted to said base, means for holding said pillar in any adjustment; said pillar having a passage-way leading from the groove in the base to the interior of the pillar, a regulating-screw, the end of which crosses said passage, a ball adapted to normally close the opening in the concave surface, a tip secured to the pillar, said tip being of low-heat-conducting material, a plate of high-heat-conducting material secured to the tip and a thermostat consisting of two

kinds of metal of different expanding qualities.

2. In combination with a burner of the character described, a thermostat consisting of a plate of high-heat-conducting qualities and two strips of metal of different expanding qualities extending side by side for a certain distance and then being reversed for the remainder of their length, as and for the purposes set forth.

3. In combination with a burner of the character described, a base having a concaved upper surface and a hole formed through the same, a ball adapted to rest upon the concaved surface and close the hole therethrough, a thermostat consisting of a high-heat-conducting plate secured to the tip of the burner and two metal strips extending downward from said plate lying side by side for a certain distance then crossing and lying side by side on the opposite sides of each other and means for adjusting the burner concentric with the base whereby the position of the hole through the concaved surface of the base will be varied relative to the strips of the thermostat, as specified.

In testimony whereof I have hereunto affixed my signature in the presence of two subscribing witnesses.

LEO HOLTSCHNEIDER.
